FEEDING MECHANISM FOR SEWING MACHINES

Harold J. Le Vesconte, Western Springs, Ill., assignor to Union Special Machine Company, Chicago, Ill., a corporation of Illinois

Application September 21, 1933, Serial No. 690,487

8 Claims. (Cl. 112—18)

The invention relates to new and useful improvements in a feeding mechanism for sewing machines, and in particular to a feeding mechanism which is adapted to be used in connection with a cup feed type of sewing machine. An object of the invention is to provide a feeding mechanism having cooperating rotating members geared together for rotation, with a means operating through one of said members for imparting feeding movements thereto, and a means operating through the other member for preventing retrograde movements in the feed members during the formation of the stitch.

A further object of the invention is to provide a feeding mechanism of the above type wherein the feeding members are disposed at the lower end of vertically arranged supporting shafts and operate to support and feed the fabric being stitched, while the operating means and the retarding means for the feeding members are disposed at the upper ends of the shaft.

A still further object of the invention is to provide a feeding mechanism of the above type wherein the operating means and the retarding means are each in the form of a clutch drum opening upwardly with the clutch parts housed within said drum.

In the drawings—

Figure 1 is a view in plan with parts broken away to show the inner structure;

Fig. 2 is a vertical sectional view through the machine showing only the feeding mechanism for operating the feed wheels of a cup feed machine, and

Fig. 3 is a detail in side elevation showing the universal connection for driving one of the feed cups, the parts being separated to show their structure.

The invention is directed to a feeding mechanism for sewing machines which includes rotating feed wheels between which the fabric to be stitched is gripped. In the present illustrated embodiment of the invention, these feed wheels are the feed cups of a cup feed type of machine. The invention, however, in its broadest aspect, may be embodied in other types of machines. One of said feed wheels is fixed to a shaft, which shaft is intermittently rotated by a clutch drum connected thereto and an intermittently operating clutch dog which engages the drum and gives the desired increments of movement thereto. The other feed wheel is connected to a shaft on which is mounted a clutch drum with which a clutch dog cooperates for preventing retrograde movements in the feed wheels during the stitch formation.

The two shafts are geared together so that movements imparted to one will be imparted to the other, and restrained movements applied to one will be likewise applied to the other.

Referring more in detail to the drawings, the invention is shown as applied to a cup feed type of machine which includes a framework or housing 1 in which is mounted a main actuating shaft 2. Extending laterally from said housing is an overhanging projecting bracket 3 preferably formed integral with the housing 1. Mounted in said projecting housing is a sleeve bearing or bushing 4 which extends some distance beneath said projecting housing. Mounted in this sleeve bearing is a shaft 5, to the lower end of which is fixed a feed cup 6. Said feed cup 6 is provided with a projecting hub 7 on its lower face, which hub is journaled in a bracket 8 attached to the main housing 1. This bracket not only steadies the shaft 5, but also supports the feed cup 6. The feed cup is fixed to the shaft 5 by a set screw 9 which may be reached through an opening 10 in the bracket. Fixed to the upper end of the shaft 5 is a drum which includes a hub portion 11, a radially projecting portion 12, and a circumferential flange 13 which projects from the radial portion 12. This drum is secured to the shaft 5 by set screws, one of which is indicated at 14. Located within this drum are clutch members, which as shown, are in the form of rollers 15, 15, 30 15. Freely mounted on the shaft is a block 16 having eccentric faces 17 with which the rollers 15 contact. There is a spring 18 associated with each roller. The block 16 is attached to a plate 19 by screws 20, 20. Fixed to the upper end of the shaft 5 is a cap 21 which bears on the plate 19 and holds said plate and block 16 in position in the clutch drum. This drum and clutch mechanism for imparting intermittent movement to a shaft per se, forms no part of the present invention, but is similar to that shown in the patent granted Long and Sliwa, November 20, 1928, No. 1,692,130.

The plate 19 is provided with an arm 22, which arm carries a ball stud and a link 23 is attached to said ball stud. The link 23 at its other end is connected to a ball mounted on a stud 24 which is adjustably attached to the arm 25 carried by a sleeve 26. This sleeve 26 is mounted for oscillation on a shaft 27. Said sleeve carries a separate projecting arm 28 to which an eccentric strap 29 is attached, and the eccentric strap 29 cooperates with an eccentric 30 on the main actuating shaft 2. When the main actuating shaft is rotated, it will impart oscillations to 55

the plate 19, and as said plate is moved in one direction, the rollers 15 will be caused to roll outward on the eccentric surfaces 17 until said rollers grip the clutch drum and then a short angular movement will be imparted to the clutch drum and through the clutch drum to the feed wheel 6.

Cooperating with the feed wheel 6 is a feed wheel 31. The feed wheel 31 is provided with a hub 32 on its outer face, and said feed wheel and hub are attached to a shaft 33 by a set screw 34. The shaft 33 is mounted in a bearing sleeve or bushing 35 which is clamped to a bracket arm 36. This bracket arm 36 is in turn fixed to a shaft 37 which is mounted in the projecting housing 3. A spring 38 bearing on a projecting lug 39 carried by the bracket and against an abutment on the projecting housing 3 normally tends to move the two feed wheels or feed cups into contact so that the fabric to be stitched will be clamped between said feed cups and presented to the stitching mechanism. These feed cups operate in the usual manner for supporting the fabric and intermittently presenting the same to the needle, remaining stationary while the needle penetrates the fabric and the stitch formation is made, after which said feed cups are given the desired angular rotation for presenting the fabric for the next stitch formation.

The shaft 33 carrying the outer feed cup is positively driven from a shaft 40 which is mounted in a bushing 41 carried in the projecting housing 3. The shaft section 40 is connected to the shaft section 33 through a universal connection. Fixed to the shaft section 33 is a laterally projecting head 42 having two diametrically opposed radial slots 43. Attached to the lower end of the shaft section 40 is a similar laterally projecting head 44 having diametrically opposed radial slots 45. Located between the two heads is a coupling member 46. Said coupling member 46 is provided with two laterally projecting lugs 47 and 48. These two lugs engage the radial slots 43 in the head 42. This coupling member is also provided with two diametrically opposed lugs 49 and 50 on the opposite face thereof which are adapted to engage the radial slots 45 in the coupling head 44. The central member of this coupling is offset at diametrically opposite points so as to provide projecting shoulders 51 at one side of the coupling member and projecting shoulders 52 arranged intermediate the first-named shoulders and located at the other side of the coupling member. The shoulders 51 may make contact with the outer face of the coupling head 43, while the shoulders 52 may make contact with the inner face of the coupling head 44. The lugs 49 and 50 are on the opposite side of the coupling from the shoulders 51, while the lugs 47 and 48 are on the opposite side of the coupling from the shoulders 52. Through this universal connection between the two shaft sections, the shaft section 33 is permitted to move about the axis of shaft 31 toward and away from the shaft 5 in order to permit relative movement of one feed cup toward and away from the other feed cup, and at the same time, the shaft section 33 is positively rotated with the shaft 40 or held from movement when said shaft 40 is restrained from movement.

Fixed to the shaft 40 is a clutch drum 53. This clutch drum 53 includes a hub 54 and a radially projecting member and a circumferential flange 55 similar to the clutch drum which is attached to the shaft 5. Located within the

clutch drum carried by the shaft 40 are rollers 56, 56, 56. These rollers are adapted to contact with the inner face of the clutch drum. Mounted loosely on the shaft 40 is a block 57 having eccentric faces with which the rollers 56 contact. There is a spring 58 associated with each roller. The block 57 is fixed to a plate 59 by means of screws 60, 60. Fixed to the upper end of the shaft 40 is a cap 61 which holds the plate and block in place in the clutch drum.

Projecting laterally from the plate is an arm 62 which is secured by a bolt 63 to the housing so that the plate 59 and the block 57 connected thereto are held from any rotating movement on the shaft 40. When the clutch rollers are out of gripping contact with the clutch drum, then the shaft 40 is free to be rotated. This occurs when the shaft is rotated in one direction. When, however, the shaft tends to rotate in the opposite direction, the rollers will at once grip the clutch drum and prevent any such rotation. The purpose of this clutch drum is to permit the shaft 40 to rotate in one direction and positively restrain said shaft from any movement in the opposite direction. The circumferential flange 13 of the clutch drum attached to the shaft 5 is provided with a gear 64, and this gear meshes with a gear 65 similarly formed on the circumferential portion 55 of the clutch drum which is fixed to the shaft 40. When the clutch drum attached to the shaft 5 has an angular rotating movement imparted thereto, a similar rotating angular movement will be imparted to the shaft 40, but, of course, in the opposite direction. This imparts rotation to the feed wheels 6 and 31 so that fabric gripped therebetween will be fed and the fabric positioned for the next needle penetration. When the clutch rollers 15 are moved in the opposite direction, they will be released from the clutch drum 13 and said rollers moved back on the surface of the clutch drum for a new gripping hold. At this time the clutch rollers 56 gripping the clutch drum attached to the shaft 40 will prevent any retrograde movement in either shaft and thus any retrograde movement in either feed wheel.

By mounting the clutch drums at the upper ends of the shafts and by putting one on one shaft and the other on the other, cups are provided which face upwardly and which can be readily supplied with lubricating oil. These cups will retain the oil so that the operating parts are practically flooded with oil. By removing the cover plate from the machine, the parts of either the clutch drum which gives movement to the shafts or the clutch drum which restrains movements thereof, are readily accessible.

The supporting bracket 36 carrying the outer feed cup can be shifted so as to separate the feed cups by means of a lever 66. This lever 66 is attached to a sleeve 67 freely mounted on the shaft 37 and having a lug 68 engaging between shoulders formed in a sleeve which is fixed to the shaft 37. This manner of separating the feed cups forms no part of the present invention, but is shown, described and claimed in the application of Oscar Quist, filed November 30, 1932, Serial No. 645,094.

While the invention is shown as applied to a cup feed type of machine, it will be understood that from certain aspects, the rotary feeding mechanism may be used in any type of machine where it is desirable to impart a feeding movement to a fabric through the aid of two cooperating feed rollers or wheels. The essential feature

consists in the mounting of the actuating clutch drum on the shaft of one of said feed-wheels and the retarding or restraining clutch drum on the shaft which operates the other feed wheel. It will also be understood that the operating clutch drum may be attached to the outer feed shaft and the restraining clutch drum attached to the inner feed shaft, if desired. It is also obvious that changes in the details of construction and the arrangement of the parts may be made without departing from the spirit of the invention as set forth in the appended claims.

Having thus described the invention, what I claim as new and desire to secure by Letters-Patent, is—

1. A feeding mechanism for sewing machines including cooperating rotating feed wheels, feed shafts for imparting movements to said feed wheels, means whereby rotations imparted to one shaft are positively imparted to the other, an actuating clutch mechanism attached to one of said shafts for imparting feeding movements to said shafts, and a restraining clutch mechanism attached to the other shaft for preventing retrograde movements in either shaft.

2. A feeding mechanism for sewing machines including cooperating rotating feed wheels, feed shafts for imparting movements to said feed wheels, means whereby rotations imparted to one shaft are positively imparted to the other, an actuating clutch mechanism attached to one of said shafts for imparting feeding movements to said shafts, and a restraining clutch mechanism attached to the other shaft for preventing retrograde movements in either shaft, one of said shafts for operating the feed wheels being formed in sections with a universal connection between said sections whereby to permit relative movement of said feed wheels toward and away from each other.

3. A feeding mechanism for sewing machines comprising a housing having a projecting portion, a shaft mounted therein for rotation about a vertical axis, a feed cup mounted at the lower end of said shaft, a second shaft mounted in said projecting portion of the housing and carrying at its lower end a feed cup, said last-named shaft being formed in sections with a universal connection therebetween, an actuating clutch drum disposed at the upper end of one shaft for imparting rotations thereto, a restraining clutch drum disposed at the upper end of the other shaft for restraining said last-named shaft from retrograde movement, and means for positively connecting said shafts whereby the actuating clutch drum imparts rotations to both shafts and the restraining clutch drum prevents both shafts from retrograde movement.

4. A feeding mechanism for sewing machines comprising a housing having a projecting portion, a shaft mounted therein for rotation about a vertical axis, a feed cup mounted at the lower end of said shaft, a second shaft mounted in said projecting portion of the housing and carrying at its lower end a feed cup, said last-named shaft being formed in sections with a universal connection therebetween, a clutch drum attached to one of said shafts at the upper end thereof, said clutch drum having a radially projecting member and a circumferential flange, actuating clutch members located within said flange for imparting rotation to the shaft, a clutch drum connected to the other shaft and having a radially projecting portion and a circumferential flange, clutching members located within said last-

named clutch drum, and means for holding said clutch members from angular movement for preventing retrograde movement of said shaft, and intermeshing gears connecting said shafts.

5. A feeding mechanism for sewing machines comprising a housing having a projecting portion, a shaft mounted therein for rotation about a vertical axis, a feed cup mounted at the lower end of said shaft, a second shaft mounted in said projecting portion of the housing and carrying at its lower end a feed cup, said last-named shaft being formed in sections with a universal connection therebetween, a clutch drum fixed to the upper end of one of said shafts and having a radially projecting member and a circumferential flange, a block having eccentric faces freely mounted on the shaft and located within said flange, rollers between the block and the flange for gripping the same, a spring associated with each roller, and a cap attached to said shaft for holding said block in said drum.

6. A feeding mechanism for sewing machines comprising a housing having a projecting portion, a shaft mounted therein for rotation about a vertical axis, a feed cup mounted at the lower end of said shaft, a second shaft mounted in said projecting portion of the housing and carrying at its lower end a feed cup, said last-named shaft being formed in sections with a universal connection therebetween, a clutch drum fixed to the upper end of one of said shafts and having a radially projecting member and a circumferential flange, a block having eccentric faces freely mounted on the shaft and located within said flange, rollers between the block and the flange for gripping the same, a spring associated with each roller, a cap attached to said shaft for holding said block in said drum, and means for imparting oscillations to said block.

7. A feeding mechanism for sewing machines comprising a housing having a projecting portion, a shaft mounted therein for rotation about a vertical axis, a feed cup mounted at the lower end of said shaft, a second shaft mounted in said projecting portion of the housing and carrying at its lower end a feed cup, said last-named shaft being formed in sections with a universal connection therebetween, a clutch drum fixed to the upper end of one of said shafts and having a radially projecting member and a circumferential flange, a block having eccentric faces freely mounted on the shaft and located within said flange, rollers between the block and the flange for gripping the same, a spring associated with each roller, a cap attached to said shaft for holding said block in said drum, a similar clutch drum, clutch block and rollers connected to the other shaft, and means operated through one of said blocks for imparting intermittent rotations to one shaft and through the other block for preventing retrograde movement of the shaft with which it is associated, and gears connecting said shafts.

8. A feeding mechanism for sewing machines comprising, in combination, a housing having a projecting member, shafts mounted in said projecting member for rotation about vertical axes, feed cups secured to said shafts and operated directly thereby, a bracket mounted on said housing and engaging the lower end of one of said shafts beneath the feed cup thereon whereby to steady said shaft, and means located entirely above said bracket for imparting intermittent feeding movements to said shaft.
